Attorneys.

UNITED STATES PATENT OFFICE.

OTTO POEPPEL, OF ESSLINGEN-ON-THE-NECKAR, GERMANY.

METHOD OF RENDERING PAPER SHEETS LOCALLY TRANSPARENT.

Application filed April 19, 1926, Serial No. 103,141, and in Germany May 20, 1925.

This invention relates to a method of rendering paper sheets locally transparent, for example sheets to be formed into window envelopes.

5 Heretofore there have been practised two methods of rendering paper sheets locally transparent.

According to one method the sheet is coated at the required locality with a suitable medium, such for example as lacquer, resin or oil which is allowed to act at normal temperature on the paper and then allowed to dry. It is an objection to this method that it involves much labour and 15 the occupation of much space and time, in that for the drying alone as much as 36 hours may be required. It is only when the operation is about completed that its success can be determined.

20 According to the second method the paper sheet is coated in a lacquering machine at the desired locality and over a selected area with a medium adapted to render the paper transparent, whereupon a gripping member 25 deposits the coated sheet on a conveyor band which conveys it to an artificially heated chamber, for example a drying oven. This mechanical method can be performed in much less time than that first described, but 30 is open to the objection that the artificial heat affects deleteriously those parts of the paper which are not coated with the medium, modifying the color or shade of the paper if colored, or turning white paper yellow.

35 The method forming the subject of the present invention avoids the objections aforesaid, in that, as contrasted with the first method, it represents a saving of labour, space and time, and, as contrasted with the 40 second method, it does not involve subjection of the uncoated paper to the influence of artificial heat with consequent risk of discoloration.

According to the invention paper sheets, 45 which have been coated locally with medium to render the coated area transparent, i. e., to form windows in the paper, are brought into the field of influence of travelling artificially heated elements of form and dimensions corresponding to the shape and size 50 of the "windows" and are maintained subject to such influence until transparency is obtained and the transparent surface completely dried.

55 In the accompanying drawing Fig. 1 is a side view, Fig. 2 a plan view, and Fig. 3 a

cross section diagrammatically illustrating an apparatus by which the invention may be carried into effect.

After the paper sheets *a* have been coated 60 at the desired locality over a predetermined area with medium adapted to render the paper transparent, for example in a rotary printing and lacquering machine, they are transferred successively from the coating or 65 lacquering machine to a conveyor band *b* into which are built heating elements *e*, which may, for example, be electrically heated, and which correspond in form and dimensions to the "windows" to be formed. 70 The conveyor is operatively connected with the lacquering machine so that it brings a heating element *e* into position beneath a sheet every time a sheet *a* is deposited on the band, the heating elements being positioned 75 to register with the localities coated with medium. The heating elements are smaller in size than the sheets *a*, or the parts of such sheets which are to be coated, so that the entire sheets are not heated, but only the 80 desired "window" parts thereof. The sheets *a* are held against the band *b* by any suitable means, as by the conventionally represented grippers *g*. The surface of each heating element *e* is located at a desired distance *d* beneath the upper surface of the band, so that the paper does not come directly in contact with the hot surface. The paper sheets travel with the band (to the right) until they are tilted, at a point over 90 the right hand roller *r'*, into a receiver *k* in which they are piled. The time taken from the application of the coating to each sheet until its transference to the receiver can be so regulated that the coating medium 95 is perfectly dried before being discharged into the receiver of receptacle *k*. The time involved may be a fraction of a minute.

The endless conveyor band, with the built-in heating-elements, is looped over two 100 rollers *r'*, *r''* connected by a chain *f*, the rollers *r'* being driven from the coating or lacquering machine *h*. The weight of the band and of the heating elements between the rollers is supported by rails or bands *s* 105 which may also serve as conductors for transferring current to the elements *e* through the medium of conductors *z*.

The distance *d* may be adjusted according to the nature of the coating medium, 110 the thickness of the paper and the temperature of the heating elements.

It is to be understood that the invention is not limited to the use of apparatus such as described and shown.

I claim:—

5 In the treatment of paper sheets to render the same locally transparent, transferring the sheets, precoated at the desired locality with medium to render the paper transparent, to the field of influence of travelling

heating elements each of the form and dimensions corresponding to those of the "windows" to be formed, and maintaining the sheets subject to such influence until the paper is transparent and the coating medium completely dried.

10 15 In testimony whereof I have signed my name to this specification.

OTTO POEPPEL.
